UNITED STATES PATENT OFFICE.

RUDOLPH CONRADER, OF ERIE, PENNSYLVANIA.

LAP.

1,109,401.

Specification of Letters Patent.

Patented Sept. 1, 1914.

Application filed December 13, 1910. Serial No. 597,013.

To all whom it may concern:

Be it known that I, RUDOLPH CONRADER, a citizen of the United States, residing at Erie, in the county of Erie and State of Pennsylvania, have invented new and useful Improvements in Laps, of which the following is a specification.

This invention relates to laps and consists in certain improvements in the construction 10 thereof as will be hereinafter fully described and pointed out in the claims.

More particularly, the invention relates to a type of lap especially adapted for finishing the interior surfaces of tubes of considerable 15 length, such as, working barrels in Artesian well pumps.

The invention is illustrated in the accompanying drawings as follows:

Figure 1 shows a plan view of the lap. Fig. 20 2 a section on the lines 2—2 in Figs. 1, 3, 4 and 5. Fig. 3 a section on the lines 3—3 in Figs. 1 and 2. Fig. 4 a section on the lines 4—4 in Figs. 1 and 2. Fig. 5 a section on the lines 5—5 in Figs. 1 and 2.

25 1 marks the lap wheel. This is formed of some soft material, and is divided longitudinally. Bars 2—2 extend through the wheel, these bars being cast in the wheel parts. The bars at one end are separated by 30 the block 3, and have the clamping blocks 4 and 5 opposite the block 3, the block 4 being perforated and the block 5 screw threaded, and the whole clamped together by a screw 6. The blocks 3, 4 and 5 with the bars are 35 preferably circular in outline in end view. The opposite end of the bars 2 are separated by the block 7 which extends from the driving head 8. Blocks 9 and 10 are arranged 40 opposite the block 7, the block 9 being perforated and the block 10 perforated and screw threaded, and the parts clamped together with the screw 11. With this arrangement of bars, it will be observed that 45 both ends of the lap wheel are similarly restrained, and have an equal tendency for outward movement so that as the lap wheel is inserted in the barrel or tube that has been ground, there is no tendency for one end of the wheel to exert greater pressure, and consequently have greater grinding effect than the opposite end. This is of great advantage in that it assures a more even surface than where the ends are not balanced.

50 The wheel is driven from the head 8 with any desired source of power, and so arranged that the lap wheel may be passed

through the tube if desired. The bars have the perforations 12 into which the metal flows as at 13, thus locking the bars against endwise movement in the wheel parts. 60 These wheels are sometimes used by rotating the work instead of the wheel. Where this is done, it is desirable to have some means for forcing the wheel parts outwardly. This may be accomplished by a 65 spring action on the bars 2, but I prefer to accomplish it by means of supplemental springs. The opposing faces of the wheel parts have the sockets 14 preferably extending to a depth of the face of the bars, and in 70 these sockets are placed coil springs 15 which force the wheel parts outwardly.

It is desirable to limit the outward movement of the wheel parts so that the tube may be given a predetermined size. To accomplish this, I perforate the bars at 16, and screw thread the perforations in one end of the bars. The bolt 17 extends through the perforation in one bar and is screwed into the screw threaded perforation in the other 80 bar. The bolt is locked in adjustment by the jam nut 18. By adjusting the bolt any limit may be fixed for the wheel parts as desired, thus giving any predetermined size to the lap wheel that may be desired. 85

I prefer to reinforce the bars adjacent to the perforation 16 by means of the plates 19 which extend into the ends of the wheel parts, and are secured to the bars 2 by means of the rivets 20. These plates so reinforce 90 the bars at this point that there is little give to them so that the outward limit of the wheel parts will not be influenced to any great extent by any change of speed of the wheel, or other conditions which might interfere with accuracy, if the bars only were depended upon. 95

In order to effect a more uniform distribution of the grinding material which is ordinarily emery and some liquid carrier, I 100 prefer to provide the faces of the wheel parts with the grooves 21. These grooves form screw threads which as the wheel advances pick up the grinding material from the surface of the tube or barrel, and carry 105 it along the wheel surface so as to distribute it. These grooves are pitched in both directions so that they will operate in either direction as the feed is reversed.

What I claim as new is:

1. In a lap, the combination of a lap wheel divided longitudinally; axially ex-

tending spring bar supports for the wheel parts; a rotatable mounting for said supports having its axis on the axis of the lap wheel; and means for limiting the outward movement of the parts.

2. In a lap, the combination of a lap wheel divided longitudinally; spring bar supports extending axially from both ends of the wheel parts; and means uniting the bars at each end of the wheel parts.

3. In a lap, the combination of a lap wheel divided longitudinally; bar supports extending axially from both ends of the wheel parts; means uniting the bars at each end of the wheel parts; and devices for limiting the outward movement of the parts.

4. In a lap, the combination of a lap wheel divided longitudinally; bar supports extending axially from both ends of the wheel parts; means uniting the bars at each end of the wheel parts; devices for limiting the outward movement of the parts; and means for adjusting said devices to vary the limit of outward movement of the parts.

5. In a lap, the combination of a lap wheel divided longitudinally, the opposing faces of the parts having spring sockets therein; axially extending bar supports for the wheel parts; a rotatable mounting for said supports having its axis on the axis of the lap wheel; and a spring in said sockets for forcing said parts outwardly.

6. In a lap, the combination of a lap wheel divided longitudinally, and having sockets in the opposing faces of the parts; bar supports extending axially from both ends of the wheel parts; means uniting the bars at each end of the wheel parts; and springs in said sockets tending to force the said parts outwardly.

7. In a lap, the combination of a lap wheel divided longitudinally; axially ex-

tending supporting bars for the wheel parts; reinforcing plates extending from the ends of the wheel parts; adjustable means for limiting the outward movement of the wheel parts acting on the portions of said bars reinforced by said plates.

8. In a lap, the combination of a lap wheel divided longitudinally; bar supports extending axially from both ends of the wheel parts; means uniting the bars at each end of the wheel parts; reinforcing plates extending from the ends of the wheel parts on said bars; and adjustable means for limiting the outward movement of the wheel parts and acting on the portions of said bars reinforced by said plates.

9. In a lap, the combination of a lap wheel divided longitudinally; and supports for the lap wheel, there being a spiral groove on the surface of the lap wheel.

10. In a lap, the combination of a lap wheel divided longitudinally; and supports for the lap wheel, there being spiral grooves pitched in both directions on the surface of said lap wheel.

11. In a lap, the combination of a lap wheel divided into segments; supports for said segments permitting the radial movement of the segments; and adjustable means limiting the outward movement of the segments; a rotatable mounting for said supports arranged with its axis on the axis of the wheel to a predetermined outer working position.

In testimony whereof I have hereunto set my hand in the presence of two subscribing witnesses.

RUDOLPH CONRADER.
